UNITED STATES PATENT OFFICE.

HERMAN F. LIPSIUS, OF DAVENPORT, IOWA.

DOOR HOLDER.

Application filed June 5, 1924. Serial No. 718,098.

To all whom it may concern:

Be it known that I, HERMAN F. LIPSIUS, a citizen of the United States, residing at Davenport, in the county of Scott and State 5 of Iowa, have invented a new and useful Door Holder, of which the following is a specification.

This invention aims to provide a simple means whereby a door may be held in any 10 position to which it may have been swung as it is opened, to the end that the door may not be closed by a draft, or otherwise.

It is within the province of the disclosure to improve generally and to enhance the 15 utility of devices of that sort to which the invention appertains.

Although a preferred form has been depicted, a mechanic, working within the scope 20 of what is claimed, may change that form without departing from the spirit of the invention.

In the drawings:—

Figure 1 shows in side elevation, a device 25 constructed in accordance with the invention and in the position which it will assume when not in use; Figure 2 is a similar view showing the device in operation; Figure 3 is a section taken about on the line 3—3 of Figure 2.

The device comprises a clamp 1, generally 30 made of sheet metal and including a base 2 and an arm 3 located at an acute angle to the base and connected to the base by a bend 4 the clamp 1 being wedge-shaped. The base 35 2, the bend 4 and the arm 3 may be provided with longitudinal corrugations 5 which strengthen the clamp without depriving the arm 3 of all of its resiliency. The free end of the base 2 is turned over to form a stop 40 flange 6. At the free end of the arm 3, eyes

7 are fashioned. The eyes hold a shaft 8 received within a socket 9, the ends 10 of which are secured to the rear surface of a lever 11 having longitudinal reinforcing ribs 12. In substance, the lever 11 is fulcrumed intermediate its ends on the arm 3, and any suitable means may be used, other than the socket 9, for fulcruming the lever.

In practical operation, the clamp 1 is slid along the floor 14 until the clamp is wedged 45 lightly between the floor and the lower edge of the door 15, the parts being in the position shown in Figure 1. Then, the lever 11 is swung in the direction of the arrow A in Figure 2, until the lower end of the lever 50 abuts against the stop flange 6, the arm 3 being bound against the lower edge of the door 15, and the parts being arranged as delineated in Figure 2. The shaft 8 is so arranged with respect to the stop flange 6 that, 55 when the parts stand as shown in Figure 2, the lever 11 is not exactly at right angles to the base 2 of the clamp 1 and, consequently, it is not likely that the lever will be dislodged accidentally from the position shown 60 in Figure 2.

What is claimed is:—

A door holder comprising a clamp fashioned from a single piece of material bent upon itself to form a base and an arm, and a 70 lever fulcrumed on the arm and cooperating with the base to expand the clamp, the free end of the base being bent upon itself to form an overhanging stop which engages with the lever to hold the lever in clamp- 75 expanding position.

In testimony that I claim the foregoing as my own, I have hereto affixed by signature.

HERMAN F. LIPSIUS.
